(57) **CLAIM**

The ornamental design for a luminaire, as shown and described.

DESCRIPTION

FIG. 1 is a front perspective view of my luminaire.

FIG. 2 is a left side view of the luminaire.

FIG. 3 is a right side view of the luminaire.

FIG. 4 is a top view of the luminaire.

FIG. 5 is a bottom side view of the luminaire.

FIG. 6 is a back view of the luminaire.

FIG. 7 is a front view of the luminaire; and,

FIG. 8 is a front perspective view of the luminaire, taken from an opposite perspective as the view of FIG. 1.

The broken lines illustrate environmental features that form no part of the claimed design.
